UNITED STATES PATENT OFFICE.

FRANCIS DU PONT THOMSON, OF ELKTON, MARYLAND.

SCALING TOOL.

Application filed March 15, 1927. Serial No. 175,625.

My invention relates to scaling tools. The object is to provide improved means for securing the head or poll to the spindle.

The scaling tool to which this invention relates is similar in operation to the pneumatic riveting hammer, except that in place of the riveting head, a head is provided with a square face having cross-corrugations or a series of points very similar to the stone dresser hammer.

In accordance with the present practice this head is removably secured to the reciprocating spindle by means of two pins projecting through the body or neck of the head and adapted to engage the annular shoulder formed by an enlarged convex end of the reciprocating spindle. This enlarged convex end of the spindle fits in a corresponding concave recess in the head, and the pins permit a certain play between the end of the spindle and the head so that the plane of the working face of the head may variously incline to the axis of the spindle as the said face operates against the ship's hull. When the sharp edges or points of the working face of the head become worn or deformed, the head is detached from the spindle for replacement or repair. The objection to the securing pins which are so positioned as to permit said angular play between spindle and head, is that they also permit lost motion between the end of the spindle and spindle seat in the head, which results in a pounding between the spindle-end and the head, and also between the spindle and the securing pins, so that these contacting parts become marred and distorted, making it difficult, in the first place to remove the pins and in the second place to fit the spindle-end into a new head.

The present invention avoids the difficulty by providing a shoulder or abutment in the head surrounding the seat for the spindle-end and interposing, between said abutment and the shoulder or abutment formed by the enlarged spindle-end, a resilient or yielding body which shall permit free angular movement of the spindle axis with respect to the head, while maintaining constant working contact between the convex spindle-end and the concave seat therefor, so that the im-

pulses of the spindle shall be communicated directly to the head without lost motion, and so that there shall be no knocking or pounding between the spindle-end and its seat and no marring or injury to the shoulder of said enlarged spindle-end, and so that the arbitrary separation of the head from the spindle and the operative engagement of the spindle-end with the head can always be secured with ease and dispatch.

Referring to the drawings, which illustrate merely by way of example a suitable embodiment of the invention:-

Fig. 1 is an elevation of the spindle-end and the head in cooperative relationship.

Fig. 2 is a vertical section of same, the spindle remaining in elevation.

Fig. 3 is a similar view with the axis of the spindle inclined to the head.

Fig. 4 is an under plan view of the head.

Similar numerals refer to similar parts throughout the several views.

The spindle-end 7 is of usual form, provided with an enlarged convex end 8, adapted to seat in a concave recess 10 in the central part of the head 11. This recess 10 communicates with a flaring opening 12 at the rear side of the head to permit of the angular movement of the spindle as indicated in Fig. 3.

This is all substantially in accordance with the present practice, which has existed for many years.

The present invention consists in the means for securing the operative relationship between the spindle 7 and head 11.

Between the edge or margin of the flaring opening 12 and the concave recess or seat 10, I provide an annular channel 13. This channel surrounds the margin of the recess 10. Into this channel is inserted a ring or washer 14 of rubber or other suitable resilient or yielding material. This ring has an inner margin 15 at its lower side, closely fitting the spindle 7 which it surrounds. From the margin 15 the inner walls of the ring incline outwardly, forming the flaring opening 16 blending with the outer flaring opening 12.

The working face of the head is cross-corrugated forming a series of cutting points 17.

When the parts are in place, the ring 14

embraces the spindle 7 just above the spindle shoulder 18 of the enlarged convex end 8, and effectually prevents accidental disengagement between the spindle and head. It also 5 maintains the convex head in constant engagement with the cooperating face of the concave seat 10, so as to prevent pounding or knocking between adjacent surfaces, at the same time it permits free rocking movement 10 of the spindle-end in the concave seat 10, as shown in Fig. 3. The tapered or wedge-shaped edge of the ring at its point of engagement with the shoulder 18, as at 19, is sufficiently yielding to permit this movement.

15. What I claim is:—

1. A scaling tool, comprising a scaling head and a reciprocating spindle associated therewith, the spindle-end being enlarged and having a rigid convex engaging face and 20 an adjacent concave formation, the head having a corresponding rigid concave seat for said convex engaging face, and resilient means, carried by the head and engaging the spindle adjacent the spindle-end, for maintaining constant working engagement between the spindle-end and seat while permitting angular movement of the head with respect to the spindle axis, during the working operation.

30. 2. A scaling tool, comprising a scaling head having a cross-corrugated working face and a reciprocating spindle associated therewith, the spindle-end having a rigid convex engaging face, the head having a corresponding rigid concave seat therefor, and resilient means, carried by the head and engaging the spindle adjacent the spindle-end, for maintaining constant working engagement between the spindle-end and seat while permitting angular movement of the head with respect to the spindle axis, during the working operation.

45. 3. A scaling tool, comprising a scaling head having a cross-corrugated working face and a reciprocating spindle associated therewith, the spindle-end having a rigid convex engaging face, the head having a corresponding rigid concave seat therefor, and resilient means, carried by the head and engaging the 50 spindle adjacent the spindle-end, for normally maintaining the spindle axis at right angles to the plane of said working face and for maintaining constant working engagement between the spindle-end and seat while permitting angular movement of the head with respect to the spindle axis, during the working operation.

60. 4. A scaling tool, comprising a reciprocating spindle and a recessed head disengagably associated therewith, the spindle-end having a rigid convex engaging face, the head having a corresponding rigid concave seat, the spindle-end seated in the recess of the head and having a rocking movement 65 therein, and resilient means, carried by the

head and engaging the spindle adjacent the spindle-end, for normally supporting the spindle substantially at right angles with the working face of the head and also for maintaining constant working engagement 70 between the spindle-end and said seat while permitting angular movement of the head, with respect to the spindle axis, during operation of the tool.

5. A scaling tool, comprising a reciprocating spindle and a recessed head disengagably associated therewith, the spindle-end having a rigid convex engaging face, the head having a corresponding rigid concave seat, the spindle-end seated in the recess of 80 the head and having a rocking movement therein, and resilient means, mounted within the head and engaging the spindle adjacent the spindle-end, for normally supporting the spindle substantially at right angles 85 with the working face of the head and also for maintaining constant working engagement between the spindle-end and said seat while permitting angular movement of the head, with respect to the spindle axis, during 90 operation of the tool.
